CLAIM

The ornamental design for a wire management device, as shown and described.

DESCRIPTION

FIG. 1 is a perspective view of a wire management device showing my new design;

FIG. 2 is an end elevational view thereof with the opposite end being a mirror image;

FIG. 3 is a side elevational, partial sectional view, taken along line 3—3 of FIG. 1 with the opposite side being a mirror image;

FIG. 4 is a broken bottom plan view showing a layered portion thereof reversely raised;

FIG. 5 is an end elevational view of a second embodiment of the design shown in FIG. 1 with the opposite end being a mirror image thereof; and,

FIG. 6 is a side elevational view of the embodiment shown in FIG. 5 with the opposite side being a mirror image.

The appearance of the top and bottom embodiment is understood to be identical to the top of the first embodiment shown in FIG. 1.

The claimed design is shown broken away in FIGS. 3, 4, and 6 for ease of illustration.
